(57) **CLAIM**

The ornamental design for a portion of a golf club head, as shown and described.

DESCRIPTION

FIG. 1 is an elevational view of a golf club head showing my new design;

FIG. 2 is a first perspective view thereof; and,

FIG. 3 is a second perspective view thereof.

The broken line immediately adjacent to the shaded area forms an unclaimed boundary of the design. The broken line showing of the remainder of the golf club head is for illustrative purposes only and forms no part of the claimed design.
